UNITED STATES PATENT OFFICE.

FRIEDRICH JACOB MARTIN HANSEN, OF COLOGNE, GERMANY, ASSIGNOR TO ROBERT ROSENTHAL, OF BASEL, SWITZERLAND.

APPARATUS FOR USE IN THE TREATMENT OF STRIPS OF PHOTOGRAPHIC FILM.

Application filed March 6, 1922. Serial No. 541,554.

To all whom it may concern:

Be it known that FRIEDRICH JACOB MARTIN HANSEN, residing at 2, I Neue Mastrichterstrasse, Cologne, Germany, has invented 5 certain new and useful Improvements in Apparatus for Use in the Treatment of Strips of Photographic Film, of which the following is a specification.

In apparatus for use in developing, fixing 10 and washing strips of photographic films, hereinafter referred to as films, difficulties are met with in connection with the means for moving the film during its passage through the baths in consequence of the 15 different degrees of extension of the film in the various baths it has to traverse in succession. In some forms it is also necessary to impart a twist to the film so that the blank or uncoated side alone comes in contact with the guide rollers.

In apparatus of this kind in which the separate baths to be traversed by the film are contained in tubes, the idea would readily suggest itself that the film should be driven 25 by means of a roller situated above said tube. Experiment, however, has shown that this is not unconditionally practicable, since, for the reason already mentioned the film must 30 be twisted inside the tubes, and there is consequently an unequal pull on the roller.

The object of the present invention is to impart motion to the film in order to pass it through the various baths so as to obviate the above difficulties. This is accomplished 35 by driving the film through the different baths, by means of a smooth roller so arranged that any unequal tension of the film is counteracted by its slip on the roller. According to this invention, this is effected by 40 operating the roller intermittently and by arranging that the adhesion between the film and the surface of the roller is so small that differences of tension in the film are equalized in its passage over the roller.

45 The accompanying drawing, which is more or less diagrammatic, illustrates an example of a developing apparatus according to this invention. Fig. 1 is a front elevation, and Fig. 2 a side elevation of the machine. The exposed film F is passed from a receptacle 1 into the first tube 2, which contains the developer. In the bottom of this tube is a roller or guide device round 50 which the film is passed so that the film passes first downwards and then upwards

in the tube. On leaving the developing tube, the film is passed over the driving roller 3, from which it receives motion in the manner described below, and is then passed, in a similar manner, into the fixing tube 4. After 60 leaving the fixing tube it is again passed over the driving roller 3, which imparts a driving motion to it. The operation proceeds in the same manner in the washing tube 5 in which the film is washed, and 65 whence it is again passed over the driving roller 3 and into the staining tube 6 containing a solution of aniline dye. From the tube 6 the film is led over a drum 7, which is faced with soft rubber in order to obtain 70 greater adhesion. The roller 7 is of larger diameter than the driving roller 3 and is connected therewith by means of a clutch 8. This clutch may be of a simple friction type, and is so arranged that the roller 7 is rotated indirectly by the roller 3 through the 75 said clutch. This friction clutch, in combination with the roller 7, is of special importance to the success of the whole arrangement. Since the diameter of the roller 7 is 80 larger than that of the driving roller 3, it tends to impart a higher velocity to the film than is transmitted to the latter by the driving roller 3 after it issues from each of the tubes; but since the roller 7 is only operated 85 by a friction clutch, said roller can only exert tension on the film to the extent permitted by the friction clutch. In consequence of this operation, the film is maintained at a tension corresponding to the adjustment 90 of the clutch. Since, according to the invention, the driving roller 3 is such that a slight degree of adhesion exists between the film and the roller, the tension imparted to the film by the roller 7 is distributed uniformly through all the tubes. Another point of special importance is that the roller is driven intermittently, and not continuously, 95 a method which offers the advantage, in connection with the uniform distribution of tension on the film, that the film receives an acceleration of motion at the various operating points on the driving roller, but then has time for the tension to become equalized during the intervals of repose. Moreover, 100 the intermittent drive offers the further advantage in connection with the film that it prevents air bubbles from remaining adherent to the film and accompanying the film into the baths.

The intermittent drive is preferably effected by means of a ratchet and pawl device as represented in the drawing. The driving roller 3 carries a ratchet wheel 9 which is moved forward to the extent of one tooth by a pawl 11 at each stroke of a rocking lever 10 one end of which is journalled on the reduced end of the roller 3, while its other end is connected to and operated by a 10 crank or an eccentric 12 which is rotated by an electromotor 13. A pawl 14 serves to prevent backward rotation.

After the film has been passed through the various tubes or baths in the manner described it passes over the roller 7 out of the apparatus in order to be dried.

It is immaterial to the spirit of the invention whether the film is passed through a plurality of separate tubes or containers 20 charged with the same or different baths, or whether the same method of drive is applied to a single tank through which the film is passed to and fro. Neither is this invention limited to any particular number of tubes or 25 compartments or kind of liquids contained therein.

What I claim and desire to protect by Letters Patent is:—

1. Apparatus for use in treating strips of 30 photographic film in which the progressive movement of the film through one or more baths is effected by means of an intermittently operated roller over which the film is passed in the form of loops, said roller having a smooth surface so that the adhesion between the film and the roller enables differences of tension on or lengthening of the film to be equalized by the slip of the strip of film on the roller.
2. An apparatus for use in treating strips of photographic film comprising a series of 40 liquid receptacles, a smooth surface roller arranged horizontally over the receptacles and a rubber or other adhesive covering for 45 that part of the roller which is over the last receptacle and means for rotating the roller intermittently.
3. An apparatus for use in treating strips of photographic film comprising a series of 50 liquid receptacles, a smooth surface roller

arranged horizontally over the receptacles, a drum loosely mounted on said roller, a frictional covering for said drum, a clutch connected between the roller and drum and means for rotating the roller intermittently. 55

4. Apparatus for use in treating strips of photographic film comprising a series of containers for developer and other liquid through which the film is to be passed, film guide devices in the bottom of the containers, 60 a common smooth surfaced driving roller over which the strip of film is passed between each container and a frictional tension device acting on the film as it passes through the apparatus for the purpose described and means for rotating the roller intermittently. 65

5. An apparatus for use in treating strips of photographic film in which the progressive movement of the film through one or 70 more baths is effected by means of a roller over which the film is passed in the form of loops, the said roller having a smooth surface so that the adhesion between the film and the roller enables differences of tension 75 on or the lengthening of the film to be equalized by the slip of the strip or film on the roller, and means for rotating the roller.

6. An apparatus for use in treating strips of photographic film comprising a series of 80 liquid receptacles, a smooth surface roller arranged horizontally over the receptacles, a drum loosely mounted on said roller, a clutch connecting said drum and roller, and means for intermittently rotating the roller. 85

7. An apparatus of the type described for use in treating a strip of photographic film comprising a roller over which the film to be treated is looped, a draw-off drum frictionally connected to said roller and of 90 greater diameter than said roller, and means for rotating the roller and through it the drum, substantially as described.

In testimony whereof I affix my signature in presence of two witnesses.

FRIEDRICH JACOB MARTIN HANSEN.
